(57) **CLAIM**

The ornamental design for a digital chronometer and length measurement device, as shown and described.

DESCRIPTION

FIG. 1 is a top plan view of a digital chronometer and length measurement device;

FIG. 2 is a side elevation view thereof;

FIG. 3 is a bottom view thereof;

FIG. 4 is a front elevation view thereof;

FIG. 5 is a rear elevation view thereof;

FIG. 6 is a side elevation view opposite FIG. 2; and,

FIG. 7 is a top perspective view of a digital chronometer and length measurement device.
